UNITED STATES PATENT OFFICE.

MILTON A. MCKEE, OF WESTERLY, RHODE ISLAND, ASSIGNOR TO C. B. COTTRELL & SONS COMPANY, OF NEW YORK, N. Y., A CORPORATION OF NEW JERSEY.

HOT BENDING-MACHINE FOR THE TREATMENT OF PRINTING-PLATES.

1,043,334.

Specification of Letters Patent.

Patented Nov. 5, 1912.

Application filed April 27, 1909. Serial No. 492,541.

To all whom it may concern:

Be it known that I, MILTON A. MCKEE, a citizen of the United States, and resident of Westerly, in the county of Washington and 5 State of Rhode Island, have invented a new and useful Improvement in Hot Bending-Machines for the Treatment of Printing-Plates, of which the following is a specification.

10 The object of this present invention is to provide a hot bending machine for the treatment of printing plates, the parts of which machine being so constructed and arranged that local pressure may be applied to the 15 required degree upon the back of a previously curved printing plate at any desired point on the same to bring the entire plate to an absolutely accurate curve so as to insure an even printing impression by the 20 plate when in use.

In the formation of a printing plate, certain portions of the plate are necessarily made thicker than other portions thereof and therefore, when the printing plate is being 25 rolled into its curved form in the usual manner, it is not always bent into a perfect curve but will be somewhat flattened at the thicker portions thereof owing to the greater resistance at these points to the curving 30 rolls.

It is to obviate the above uneven curving of the plate that this present invention is directed.

This invention furthermore consists more 35 particularly in the provision of a machine provided with a bending box comprising heated stationary and movable members arranged to receive a printing plate between them; means being provided for applying 40 pressure locally to the back of the plate while held between the stationary and movable heated members of the bending box.

In the accompanying drawings, Figure 1 represents the machine in side elevation, 45 Fig. 2 represents the machine in end elevation, the upper member of the hot bending box being shown in full lines in its lowered position and in dotted lines in its raised position, Fig. 3 is a transverse vertical section 50 taken in the plane of the line A—A of Fig. 1, the pressure shoe and its screw being shown in full lines in its vertical position and in dotted lines in another position, Fig. 4 represents the machine in top plan, and 55 Fig. 5 is a detail longitudinal vertical sec-

tion taken in the plane of the line B—B of Fig. 2.

The hot bending box comprises a lower stationary member 1 and an upper movable member 2, which members are kept at the 60 desired degree of heat for permitting the proper treatment of the printing plate, not shown herein. Any suitable means may be employed for heating the members of the hot bending box, such, for instance, as gas 65 burners 3 and 4.

The lower member of the hot bending box is provided with an open-ended semi-cylindrical recess 5 for receiving the curved printing plate therein and the upper member of 70 the hot bending box is curved semi-cylindrically for engaging the back of the printing plate when located within the hot bending box.

Legs 6 depend from the stationary lower 75 member 1 of the hot bending box and form a suitable support therefor to bring the box up to the desired height for ready manipulation of the printing plates. These legs 6 are arranged in pairs and are spaced rigidly 80 apart by tie rods 7.

The means which I have shown for moving the upper member of the hot bending box in a right line toward and away from the lower member, is constructed, arranged 85 and operated as follows:—Vertical lifting rods 8 extend through and are guided in their movements by the lower member of the hot bending box and are rigidly secured at their upper ends to the laterally extended 90 arms 9 of the upper member of the hot bending box. In the present instance, these arms are shown as secured to said upper member by bolts 10 and the upper ends of the lifting rods 8 are provided with shoulders 11 between which and nuts 12 the arms 9 are secured. These arms 9 are of yoke form, as clearly shown in Fig. 4, to provide room for the segment to be hereinafter described. The lower ends of the lifting rods 8 are 100 provided with racks 13 which mesh with pinions 14 fixed to the ends of a rock shaft 15 mounted in suitable bearings provided by hangers 16 depending from the lower member of the hot bending box. A weight 105 17 attached to the free ends of arms 18 fixed to the rock shaft 15 tends to rock the shaft in a position to lift the upper member of the hot bending box away from the lower member. An arm 19 fixed to the rock shaft 110

15 is provided with adjusting screws 20, 21, engaging the opposite sides of an abutment 22 upon a trip arm 23 loosely mounted on the cross shaft 15 so that the position of the 5 said arm with rotative relation to the cross shaft 15 may be accurately adjusted.

It is to be understood that when the arms 19 and 23 are adjusted, they will both move together with the cross shaft 15.

10 A tripping device for engaging the free end of the arm 23 when the upper member of the hot bending box is lowered into engagement with the back of the printing plate, is provided, which tripping device 15 is constructed, arranged and operated as follows:—A rock shaft 24 is mounted in one pair of legs 6 and has fixed thereto an arm 25 arranged to engage the arm 23 on the cross shaft 15 to hold the weight 17 raised 20 and the upper member of the hot bending box lowered until the arm 25 is released from the arm 23. A foot lever 26 is pivoted at 27 to one pair of legs 6 and is connected by a rod 28 to an arm 29 fixed to the rock 25 shaft 24. A spring 30 surrounds a rod 31 connected at one end to an arm 32 fixed to the rock shaft 24 and having its other end sliding through a guide 33 on one of the pairs of legs 6, which spring 30 is interposed between the said guide 33 and a collar 34 on the rod 31, tending to hold the 30 arm 25 in the path of the arm 23 on the rock shaft 15.

The means which I have shown for forcing the upper member of a hot bending box toward the lower member thereof a sufficient distance to permit the interlocking of the tripping device is also the means which I employ for applying local pressure to the 35 back of the printing plate, which means is constructed, arranged and operated as follows:—A double segment, comprising two members 35, 36, has its base secured rigidly to the top of the lower stationary member 40 of the hot bending box, as, for instance, by bolts 37, which segment spans the upper movable member of the hot bending box and also the recess 5 in the lower stationary member. This segment is cut away a sufficient 45 distance to permit the upper member to move away from the lower member a limited distance, the said segment serving as a stop to limit the upward movement of the upper member away from the lower member.

50 A hand screw 38 has a screw threaded engagement with and extends through a block 39 provided with trunnions 40, 41, rotatably mounted in the members 35, 36, of the segment. This hand screw 38 is provided with 55 a suitable handle 42 for turning the same. The lower end of this hand screw 38 is provided with a shoe 43 arranged to travel along a curved plate 44 secured along the concave face of the upper member of the 60 hot bending box about midway its ends.

This shoe 43 is provided with a stud 45 uprising therefrom and entering an axial recess 46 in the lower end of the hand screw 38 for permitting a limited movement of the shoe and hand screw toward and away from each other without disengaging the two. 70

A double handled latch 47 has a sliding engagement with the shank of the hand screw 38, which latch is fitted to travel along the double segment 35, 36, as the hand screw is swung into different angular positions with respect to the upper member of the hot bending box, said latch being fitted to drop into any pair of a series of notches 80 48 in said segment, for holding the hand screw against rocking movement when adjusted into its desired angular position but permitting a longitudinal movement of said hand screw. 85

In operation, supposing the hand screw 38 to be unscrewed and the upper member of the hot bending box held at the limit of its raised position by the weight 17; the curved printing plate is inserted into position 90 within the recess 5 between the upper and lower members; the hand screw being in its vertical position. The hand screw 38 is then screwed inwardly thus forcing the upper member downwardly into clamping engagement with the printing plate. As this upper member moves downwardly, the lifting bars 8 will also be moved downwardly and their racks 13 will rotate the pinions 14 and thereby rock the rock shaft 15. This 100 will raise the arm 18 and thereby the weight 17 and lower the interlocked arms 19 and 23. As the upper and lower members are brought into their clamping position, the arm 23 will be swung downwardly sufficiently to permit the arm 25 of the tripping device to swing into position above the arm 23, as clearly shown in Fig. 1, thus locking the upper and lower members of the hot bending box in their clamping position. 105 The hand screw 38 may then be unscrewed sufficiently to permit its free rocking movement. The double handled latch 47 is then released from its engagement with the double segment and the hand screw is then 110 rocked into any desired angular position, thus moving its shoe 43 along the curved plate 44 to any position where it is desired to exert a local pressure upon the back of the printing plate to insure its proper curvature. The latch 47 may then be inserted into its adjacent pair of notches 48 in the double segment 35, 36, for holding the hand screw in position. The hand screw may 115 then be screwed inwardly to the desired amount to exert the required pressure upon the back of the plate. After the plate has been treated, the latch 47 may be released from the segment and the hand screw unscrewed and swung into its vertical position. 120

125 The latch 47 may then be inserted into its adjacent pair of notches 48 in the double segment 35, 36, for holding the hand screw in position. The hand screw may then be screwed inwardly to the desired amount to exert the required pressure upon the back of the plate. After the plate has been treated, the latch 47 may be released from the segment and the hand screw unscrewed and swung into its vertical position. 130

The foot lever 26 may then be depressed for swinging the arm 25 of the tripping device into a position to release the arm 23 of the rock shaft 15. The upper member of the 5 hot bending box will be automatically moved away from the lower member under the influence of the weight 17 until stopped either by the contact of the upper member with the hand screw or with the segment. The 10 printing plate may then be removed and another one inserted for treatment.

It will be seen that a machine constructed, arranged and operated substantially as herein shown and described, can be used for the 15 rapid treatment of printing plates to correct any slight irregularities in their curvature, the machine at the same time being very simple and rapid in operation.

It is evident that various changes might 20 be resorted to in the construction, form and arrangement of the several parts without departing from the spirit and scope of my invention; hence I do not wish to limit myself strictly to the structure herein set forth, 25 but

What I claim is:—

1. In a machine of the character described, a hot bending box comprising stationary and movable members arranged to receive a 30 previously curved printing plate between them, means for bringing the members into clamping engagement with the plate and swinging means for applying pressure locally to the concave back of the said plate 35 at different points thereon.

2. In a machine of the character described, a hot bending box comprising stationary and movable members arranged to receive a printing plate between them, means tending 40 to separate the members and means for bringing the members into clamping engagement with the plate and for applying pressure locally to the back of said plate at any desired point thereon.

3. In a machine of the character described, a hot bending box comprising stationary and movable members arranged to receive a printing plate between them, means tending 50 to separate the members, means for bringing the members into clamping engagement with the plate and means for locking the members in their clamping position.

4. In a machine of the character described, a hot bending box comprising stationary 55 and movable members arranged to receive a printing plate between them, means tending to separate the members, means for bringing the members into clamping engagement with the plate and for applying pressure 60 locally to the said plate and means for locking the members in their clamping position.

5. In a machine of the character described, a hot bending box comprising stationary 65 and movable members arranged to receive a

printing plate between them, means tending to separate the members, means for bringing the members into clamping engagement with the plate and a tripping device for locking the members in their clamping position. 70

6. In a machine of the character described, a hot bending box comprising stationary and movable members arranged to receive a printing plate between them, means tending 75 to separate the members, means for bringing the members into clamping engagement with the plate and for applying pressure locally to the said plate and a tripping device for locking the members in their clamping position. 80

7. In a machine of the character described, a hot bending box comprising stationary and movable members arranged to receive a previously curved printing plate between them and a hand screw pivotally mounted on the stationary member, capable of being 85 swung into different positions with respect to the plate and fitted to engage the movable member for applying pressure locally to the concave back of the said plate at different points thereon. 90

8. In a machine of the character described, a hot bending box comprising stationary and movable members arranged to receive a 95 previously curved printing plate between them and a hand screw pivotally mounted on the stationary member, capable of being swung into different positions with respect to the plate and fitted to engage the movable member for bringing the members into clamping engagement with the plate and for applying pressure locally to the concave back of said plate at different points thereon. 100

9. In a machine of the character described, a hot bending box comprising stationary and movable members arranged to receive a printing plate between them, means tending 105 to separate the members and a hand screw mounted on the stationary member and fitted to engage the movable member for bringing the members into clamping engagement with the plate. 110

10. In a machine of the character described, a hot bending box comprising stationary and movable members arranged to receive a printing plate between them, means tending 115 to separate the members and a hand screw pivotally mounted on the stationary member and fitted to engage the movable member for bringing the members into clamping engagement with the plate and for applying pressure locally to the said plate. 120

11. In a machine of the character described, a hot bending box comprising stationary and movable members arranged to receive a printing plate between them, means tending 125 to separate the members, a hand screw pivotally mounted on the stationary member and fitted to engage the

movable member for bringing the members into clamping engagement with the plate and for applying pressure locally to the said plate, and a manually operated tripping device for locking the members in their clamping position.

12. In a machine of the character described, a hot bending box comprising stationary and movable members arranged to 10 receive a printing plate between them, a hand screw pivotally mounted on the stationary member and fitted to engage the movable member for applying pressure locally to said plate and means for supporting the screw in its different angular positions.

13. In a machine of the character described, a hot bending box comprising stationary and movable members arranged to 20 receive a printing plate between them, a hand screw pivotally mounted on the stationary member and fitted to engage the movable member for bringing the members into clamping engagement with the plate and for applying pressure locally to the said plate and means for supporting the screw in its different angular positions.

14. In a machine of the character described, a hot bending box comprising stationary and movable members arranged to 30 receive a printing plate between them, means tending to separate the members, a hand screw pivotally mounted on the stationary member and fitted to engage the 35 movable member for bringing the members into clamping engagement with the plate and for applying pressure locally to the said plate, means for supporting the screw in its different angular positions and a manu- 40 ally operated tripping device for locking the members in their clamping position.

15. In a machine of the character described, a hot bending box comprising stationary and movable members arranged to 45 receive a printing plate between them, means tending to separate the members comprising a rock shaft having a rack and pinion engagement with the movable member and a weight tending to rock the said shaft 50 and means for bringing the members into clamping engagement with the plate.

16. In a machine of the character described, a hot bending box comprising stationary and movable members arranged to receive a printing plate between them, 55 means tending to separate the members comprising a rock shaft having a rack and pinion engagement with the movable member and a weight tending to rock the said shaft, and means for bringing the members into 60 clamping engagement with the plate and for applying pressure locally to the said plate.

17. In a machine of the character described, a hot bending box comprising stationary and movable members arranged to 65 receive a printing plate between them, means tending to separate the members comprising a rock shaft having a rack and pinion engagement with the movable member and a weight tending to rock said shaft, 70 means for bringing the member into clamping engagement with the plate, and a manually operated tripping device for locking the members in their clamping position comprising an arm carried by the rock shaft 75 and a spring pressed arm arranged to engage said rock shaft arm.

18. In a machine of the character described, a hot bending box comprising stationary and movable members arranged to 80 receive a printing plate between them, means tending to separate the members comprising a rock shaft having a rack and pinion engagement with the movable member and a weight tending to rock said shaft, 85 means for bringing the members into clamping engagement with the plate and for applying pressure locally to the plate, and a manually operated tripping device for locking the members in their clamping position 90 comprising an arm carried by the rock shaft and a spring pressed arm arranged to engage said rock shaft arm.

In testimony, that I claim the foregoing as my invention, I have signed my name in 95 presence of two witnesses, this twenty-sixth day of April, A. D. 1909.

MILTON A. MCKEE.
